UNITED STATES PATENT OFFICE.

ARTHUR C. HITCHCOCK, OF DECORAH, IOWA, ASSIGNOR OF ONE-HALF TO
FRANK E. BAKER, OF SAME PLACE.

FIRE-ESCAPE.

SPECIFICATION forming part of Letters Patent No. 276,969, dated May 1, 1883.

Application filed February 16, 1883. (No model.)

To all whom it may concern:

Be it known that I, ARTHUR C. HITCHCOCK, of Decorah, in the county of Winneshiek and State of Iowa, have invented certain new and useful Improvements in Fire-Escapes; and I do hereby declare that the following is a full, clear, and exact description of the invention, which will enable others skilled in the art to which it appertains to make and use the same, reference being had to the accompanying drawings, which form a part of this specification, and in which—

Figure 1 is a front view of a window and part of the wall of a house provided with my improved fire-escape. Fig. 2 is a vertical section through the same, and Fig. 3 is a detail view.

Similar letters of reference indicate corresponding parts in all the figures.
20 My invention has relation to fire-escapes; and it consists in the improved construction and combination of parts of an escape, consisting of a flexible ladder adapted to be wound upon a shaft in a box, and having means for 25 winding it up and braking it in its descent, as hereinafter more fully described and claimed.

In the accompanying drawings, the letter A indicates a box adapted to be fastened upon the wall of a house above the window, and 30 having a shaft, B, journaled in bearings in its end pieces. This shaft is provided at one end, outside the end piece of the box, with a crank, C, and at the other end, inside the end piece of the box, with a wheel, D, having a flat rim, 35 E, upon which a brake, F, consisting of a lever, G, hinged upon one side of the box and having a brake-shoe, H, near its fulcrum, bears, serving to regulate the speed of descent of the flexible ladder I, which is fastened to the shaft. 40 This ladder consists of two strips, J, of flexible material—leather or flexible metallic webbing—connected by rounds K, preferably of steel, riveted or otherwise fastened to the strips,

and may be wound upon the shaft when not used, the whole contained inside the box. The 45 under side of the box is slotted longitudinally, and provided with two anti-friction rollers, L, of the same length as the width of the ladder, which serve to allow the ladder to pass out of the box without resistance.

A cord, M, is fastened to the outer free end of the brake-lever, and passes out of the box, down alongside of the ladder, so that the first person descending may descend with the ladder, standing upon one of the rounds, and govern his speed by means of the said cord actuating the brake.

The box may be made, as shown in the drawings, with the outside and bottom in one piece, and curved, and may extend the full width of 60 the window, forming an ornamental cornice.

By constructing the escape in such a manner that the speed of the descent of the ladder may be governed by the brake having its cord extending the full length of the ladder, it will 65 be seen that it may be used immediately as thrown outside the window, the first person descending with it, whereupon it may be used in the usual manner by persons following.

Having thus described my invention, I claim 70 and desire to secure by Letters Patent of the United States—

As an improvement in fire-escapes, the combination and arrangement, as described, of the box A, slotted longitudinally in the bottom, rollers L, shaft B, wheel D, crank C, brake F, cord M, and flexible ladder I, all constructed to operate as and for the purpose shown and set forth.

In testimony that I claim the foregoing as 80 my own I have hereunto affixed my signature in presence of two witnesses.

ARTHUR C. HITCHCOCK.
